TOY PUNCH MACHINE OR SIMILAR ARTICLE

Russell A. Fritts, Elizabeth, N.J., assignor to The Singer Manufacturing Company, Elizabeth, N.J., a corporation of New Jersey

Filed Mar. 3, 1961, Ser. No. 64,139

Term of patent 14 years

(Cl. D34—15)

FIG. 1 is a front perspective view of a toy punch machine showing my new design, and

FIG. 2 is a rear perspective view of the toy punch machine shown in FIG. 1.

The essential features of my design reside in the portions shown in full lines.

I claim:

The ornamental design for a toy punch machine or similar article, substantially as shown and described.
